UNITED STATES PATENT OFFICE.

THOMAS HOLT AND JOHN WILLIAM HOLT, OF WALSHAW, BURY, ENGLAND.

WEAVING OF QUILTS, COUNTERPANES, BEDSPREADS, AND SIMILAR ARTICLES.

Application filed February 16, 1921. Serial No. 445,422.

To all whom it may concern:

Be it known that we, THOMAS HOLT and JOHN WILLIAM HOLT, both British subjects, residing at Walshaw, Bury, county of Lancaster, England, have invented certain new and useful Improvements in the Weaving of Quilts, Counterpanes, Bedspreads, and Similar Articles, of which the following is a specification.

10 This invention relates to improvements in the manufacture of quilts, counterpanes, bedspreads and similar articles which are woven with loose and tight warps to give a crimped or crinkled face to the fabric and is 15 designed to weave a crimped, crinkled or puckered cloth with a coloured figure upon it or a coloured ground cloth with a crimped, crinkled, or puckered figure upon it.

It consists in weaving simultaneously with 20 two sets of warps, a crimp warp and a figuring warp, of different colours and under different tensions, the crimp warp of grey or unbleached yarn for example, operated by healds under light tension, and the figuring warp of coloured yarn operated by a 25 jacquard under great tension and one or more wefts, preferably only one, the design being produced on both sides.

The invention will be fully described with 30 reference to the accompanying drawings:—

Fig. 1 is a drawing in plan or draft.

Fig. 2 is a lifting plan where the ground cloth is a twill weave.

Fig. 3 is a lifting plan where the ground 35 cloth is a satin weave.

Fig. 4 is a lifting plan where the ground cloth is a plain weave.

Fig. 5 is a section of the cloth across the 40 weft threads showing a section as made by the draft in Fig. 1 and the lifting plan in Fig. 4.

Fig. 6 is another section of the cloth across the weft threads.

Fig. 7 is a plan of woven cloth showing 45 the figuring warp *b* in colour worked up on to the pattern.

The crimp warp *a* is made from grey or bleached yarn and is drawn through and operated by healds the tension on this warp 50 being very light. This warp weaves in a twill, satin, or plain weave as may be required.

The figuring warp *b* is made of coloured 55 yarn and is drawn through the mails of jacquard harness and operated by a jac-

great. The figuring warp *b* may contain only half or less than half the number of threads contained in the crimp warp *a* and may be worked to form figure of ground 60 as may be desired.

The effect is obtained by having practically no weight at all on the crimp yarn *a* and stitching this drifting cloth in an endless variety of designs by bringing the taut 65 coloured figuring yarn *b* to the surface where required. By this means the crimp warp *a* along with the weft *c* forms a crimped, crinkled or puckered cloth somewhat similar to the well known crimped or crinkled paper, and the coloured figuring warp *b* by interweaving forms a coloured figure upon a crimped ground cloth or a grey or white crimped figure upon a 70 coloured ground as may be desired according to the design.

This makes a cloth which can be used either side as the face side.

The portion marked A Fig. 6 shows one 80 method of forming the coloured ground cloth, the portion marked B shows the crimped figure upon the coloured ground cloth and portion marked C Figs. 5 and 6 shows the coloured figure upon the crimped ground cloth.

The crimp yarn *a* instead of being white or grey may be of a different colour to the figuring yarn *b*.

Either a single lift or double lift jacquard may be used and the jacquard may 90 lift every pick or it may remain lifted for two or more picks and in this way a saving in jacquard cards is effected.

What we claim as our invention and desire 95 to protect by Letters Patent is:—

1. A single ply fabric comprising a weft and two warps interwoven, one of said warps being under great tension and the other of said warps being woven under loose tension with said weft, forming a crinkled 100 drifting cloth interwoven with said first mentioned warp in parts, so as to embrace both sides thereof, and in parts permitting said first mentioned warp to appear on the surface of said fabric, on one or the other sides of said drifting cloth, the latter being more crinkled opposite the exposed parts of said first mentioned warp than where said warp and drifting cloth are interwoven.

2. A single ply fabric comprising a weft and two warps interwoven, one of said warps being under great tension and the

other of said warps being woven under loose tension with said weft forming a drifting cloth of crinkled character said first mentioned warp in parts, so as to embrace both sides thereof, and in parts permitting said first mentioned warp to appear on the surface on either side of said fabric on one or the other sides of said drifting cloth, the latter being more crinkled opposite the exposed parts of said first mentioned warp than where said warp and drifting cloth are interwoven, said drifting cloth in those

parts in which said first mentioned warp appears on the surface being relatively more crinkled than in other parts. ¹⁵

In testimony whereof we have hereunto set our hands in presence of two subscribing witnesses.

THOMAS HOLT.
JOHN WILLIAM HOLT.
